UNITED STATES PATENT OFFICE.

PATRICK FRAZIER, OF BRECKENRIDGE, TEXAS, ASSIGNOR OF ONE-FOURTH TO JAMES W. WASH AND ONE-FOURTH TO KEITH MUTERSPAUGH, BOTH OF BRECKENRIDGE, TEXAS.

SUPPORT FOR FLOOR BOARDS OF AUTOMOBILES.

Application filed May 7, 1923. Serial No. 637,308.

To all whom it may concern:

Be it known that I, PATRICK FRAZIER, a citizen of the United States of America, and resident of Breckenridge, in the county of Stephens and State of Texas, have invented certain new and useful Improvements in Supports for Floor Boards of Automobiles, of which the following is a specification.

This invention relates to attachments for automobiles, and particularly to means for supporting floor boards of automobiles.

It is an object of this invention to provide novel means adapted to be supported by any of the housings under the floor, and the device may, of course, be applied to the fly wheel, transmission, or crank casing of an automobile, or, in fact, to any of the housings which may be immediately below the floor.

The invention is, however, disclosed with special reference to its association with a well known make of automobile, and those skilled in the art will immediately recognize what the inventor has in mind.

In the present embodiment of the invention, it is an object to provide a bracket-like support adapted to be attached or anchored in place by fastenings that are employed for holding the inspection plate of the gear case of the said automobile.

It is a further object of this invention to provide novel means whereby the front floor board or boards may be supported; and furthermore, it is an object to provide means whereby the front floor board or boards as well as the rear floor board may be supported.

It is a further object of this invention to produce supports of the character indicated which can be readily applied to or removed from the casings mentioned.

With the foregoing and other objects in view, the invention consists in the details of construction, and in the arrangement and combination of parts to be hereinafter more fully set forth and claimed.

In describing the invention in detail, reference will be had to the accompanying drawings forming part of this application wherein like characters denote correspond-

ing parts in the several views, and in which—

Figure 1 illustrates a plan view of machinery casings with a device embodying the invention applied thereto;

Figure 2 illustrates a side elevation thereof;

Figure 3 illustrates a plan view in which the device is intended for use in supporting all of the floor boards of the automobile;

Figure 4 illustrates a view in elevation thereof;

Figures 5 and 6 illustrate views in plan and side elevation, respectively, embodying a modified construction;

Figure 7 illustrates a plan view of a still further modification; and

Figure 8 illustrates a perspective view of the main member of the support shown in Fig. 5.

In these drawings, 5 denotes a case having an inspection plate 6 that is secured to the case by fastenings 7 such as screws or the like.

In applying the invention to a casing of the character just described, certain of the securing screws are employed, but it is usually necessary, or desirable, to substitute screws of greater length than those of the conventional type employed on the said automobile. In installing the invention, therefore, the central screws are removed and a bridge-piece 8 is applied over the inspection plate, the said bridge-piece following generally the contour of the said inspection plate, but being clear thereof except where the feet 9 of the bridge-piece rest on the flanges of the plate and to which they are anchored by the fastenings 7. The bridge-piece has an arm 10 which projects forwardly and terminates in a downwardly extending flange 11 that rests on the fly wheel housing 12.

It will be seen from an inspection of the drawing that the arm is inclined to proper degree, in order that the front floor boards will be supported in the positions in which they are now supported in the automobile to which reference has been made.

In Figures 3 and 4, the same general

provision is made for supporting the front floor boards, in that a bridge-piece 13 is secured by the fastenings 14 to the casing with the inspection plate 15, and the arm 16 projects forwardly from the bridge-piece, but in this last mentioned embodiment of the invention, there is a rearwardly extending arm 17 that is approximately horizontally supported by a bracket 18 that extends from its under side, the said bracket having a saddle 19 which partially embraces the rounded surface 19^a of the gear casing so that the arm is braced to a degree that it will support unusual weights without permitting the floor boards to sag or bend.

It will be seen from an inspection of the drawing that either form of the invention can be made as a one-piece structure and that it can be secured in place by the two anchoring elements just described. The simple nature of the devices renders it possible to accomplish their manufacture inexpensively, and they have proven efficient and satisfactory in use.

In the modification shown in Fig. 5, the board-supporting element comprises an integral structure having a central portion 20, the upper surface of which is approximately parallel with supporting plate 21, and there is a rearward extension 22, the upper surface of which is approximately horizontal, although these configurations may be changed in order that the floor boards may be given the proper pitches, according to the type of automobile on which they are used. The forward extension 23 is of increased height for a portion of its length and then tapers to produce a clearance 24 which will permit the extension to overlie a portion of the casing of the motor.

The supporting member has transverse slots 25 and 26 that receive the straps or anchoring elements 27 and 28, respectively, the said anchoring elements having a fastening 29 through them into the casing, the said fastening serving also to secure the face plate 21 in place.

The lower edge of the member has lugs or projections 30 and 31 which constitute feet or supports which lie against the surface of the plate.

In that form of the invention shown in Fig. 7, two board-supporting elements 32 and 33 are employed, and they are arranged in spaced relation to each other, each being approximately parallel with an edge of the plate 34. These members are secured in place by fastenings 35 such as are employed for securing the plate to the casing.

The members 32 and 33 may be of the general configuration shown in Fig. 8, and when the form shown in Fig. 7 is used, the straps or fastenings may be omitted.

I claim:—

1. In a support for floor boards, a bridge-piece adapted to be secured to a casing of a power plant of an automobile, the said bridge-piece having an arm projecting therefrom on an incline, and means for supporting the end of the arm remote from the bridge-piece.

2. In a support for floor boards, a bridge-piece adapted to be secured to a casing of a power plant of an automobile, an arm extending forwardly from the bridge-piece and having a downwardly extending flange adapted to rest on another portion of the casing of the power plant, as and for the purpose described.

3. In a support for floor boards, a bridge-piece adapted to be secured to a casing of a power plant of an automobile, an arm extending forwardly from the bridge-piece and having a downwardly extending flange adapted to rest on another portion of the casing of the power plant, and a rearwardly extending arm supported by the bridge-piece, and means for supporting the end of the last mentioned arm remote from the bridge-piece.

4. In a support for floor boards, a bridge-piece adapted to be secured to a casing of a power plant of an automobile, an arm extending forwardly from the bridge-piece and having a downwardly extending flange adapted to rest on another portion of the casing of the power plant, a rearwardly extending arm supported by the bridge-piece, a bracket under the last mentioned arm, and a saddle constituting a part of the said bracket adapted to partially embrace the curved surface of the casing of the said power plant.

5. In a support for floor boards, a board-supporting element adapted to overlie and be supported on a casing of a power plant of an automobile, the said supporting element having transversely disposed grooves, and straps lying in the grooves having their ends anchored to the casing.

6. In a support for floor boards of automobiles, board-supporting elements superimposed on a casing of a power plant of an automobile in spaced relation to each other, and means for securing the said elements to the said casing.

PATRICK FRAZIER.
